CLINOMETER

Frank V. Bell, Stoney Creek, Ontario, Canada

Application May 27, 1949, Serial No. 95,678
In Canada May 28, 1948

3 Claims. (Cl. 33—206)

1

My invention relates to clinometers for use upon mobile road grading machinery and the like, and the object of the invention is to provide a clinometer for attachment to the moldboards or cutting blades of road grading or building vehicles; the clinometer constituting a means whereby the gradient cut of the road crown may be readily maintained while the grading vehicle is in motion.

It is usual to form the ball or mercury races of clinometers from glass tubing, but in mounting them on road grading machinery blades or moldboards the incidence of breakage has been found to be extremely high, such breakage being due to the vibration of both the blades and the vehicle. To overcome this shattering of the tubes, tubes of plastic or bendable material have been experimented with, but it was found that plastic tubes would not hold the precisely uniform curvature when held in ordinary mounts.

The principal object of the invention then, is to provide a mount for plastic tubes in which such a tube is clamped between members, at least one of which is machined or otherwise finished at precisely the proper curvature and the tube pressed against the curvature of that particular member, or both members, so that it is permanently set at the proper uniform curvature.

The clinometer is designed to be instantly readable from a distance by the operator of the vehicle irrespective of the angle from which the clinometer is viewed; the clinometer being particularly constructed to withstand violent vibration and temperature changes without shattering or going out of adjustment.

In another form of the invention a globule of mercury in the tube of the clinometer is utilized as a means for closing selected electric circuits provided to energize electric motors, solenoids or the like, which actuate the gradient setting and control mechanisms, whereby a uniform gradient is automatically maintained while the grading vehicle is in motion.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a front elevational view of the clinometer.

Figure 2 is a vertical cross-sectional view through the clinometer.

Figure 3 is an exploded front elevational view of the clinometer.

5 The tube carrying frame of the clinometer is of rectangular shape and comprises a pair of upper and lower tube clamping members 2 and 3 and a pair of spacing end blocks 4. The clamping member 2 has a convex lower edge 5 and the 10 clamping member 3 a concave upper edge 6, at least the upper edge of the lower member 3 having a precisely uniform curvature.

The tube 7 is formed of a shatter proof transparent bendable material, such as plastic, having 15 suitable removable plugs 8 in each end, and contains a suitably sized ball or mercury globule.

The clamping members 2 and 3 are drawn together by bolts 10 which extend through suitably positioned orifices 9 in the members and 20 spacing end blocks 4. When the clamping members are drawn together by the bolts, their edges 5 and 6 engage and grip the tube, pressing it into the desired accurate curve, the tube being of course more or less preformed.

25 The spacing blocks 4 are dimensioned to retain the members 2 and 3 in the desired spaced relationship when the tube is clamped. Upon reference to Figure 2 it will be seen that the lower edge 5 of the member 2 is rabbeted or recessed to grasp the tube, and that the edge 6 of the member 3 is flat.

The tube engaging portions of the members 2 and 3 are formed with cut-away sloping sides 11 so as to expose the tube 7 and its ball or 30 mercury globule 24 to the maximum extent. The tube engaging portion of the member 3 carries suitable graduation marks 12 which are carried upon the side walls 11 and upon the tube engaging edge 6.

The tube carrying frame is mounted between 40 a pair of vertical plates 13 and 14 extending upwardly from a base plate 15 adapted to be bolted to a moldboard or element 16 of the equipment carrying the clinometer.

45 The tube frame is secured between the plates 13 and 14 by a bolt 17 passing through the plates and the frame. To effect adjustment of the level of the frame in relation to the moldboard or element 16, the plate 13 carries a pair of horizontal lugs 18 through which adjusting screws 19 engage the under face of the member 3. It will be understood that the frame may be swung about the bolt 17 by adjustment of the screws 19.

To provide automatic control, a plurality of 50 electrodes 20 are carried within the member 2.

and project downwardly through orifices 21 in the tube 7 to the vicinity of the bottom of the tube, where their points may be contacted by the mercury globule 24. The electrodes 20 are encased in suitable insulating sleeves 22 in the member 2, and carry binding posts 23 upon their upper ends.

In equipment of the character to which the clinometer is applied, the adjusting movements of the moldboards or blades are generally effected hydraulically, though other gear mechanisms are sometimes used. With my automatic gradient control clinometer, the mechanisms are preferably operated by electric motors, solenoids or the like (not shown), which are energized by electrical circuits closed by the mercury globule 24 simultaneously contacting two of the electrodes 20 to bridge the gap and close the circuit to a motor or solenoid.

In the manual gradient control of mobile grading equipment, the operator actuates the control mechanism to maintain the moldboard at the correct gradient inclination, and in the visual use of my clinometer, the operator through manual control retains the mercury globule at a predetermined graduation point.

With automatic gradient control in operation, the closing or opening of the electrical circuits through the electrodes 20 regulates the hydraulic or mechanical controls of the cutting edges of the equipment, keeping them at a constant and uniform gradient regardless of the irregularity of the ground over which they are passing.

From the foregoing description it will be apparent that the use of any clinometer is particularly applicable to construction without benefit of grade stakes, straight edges, levels, lines or surveying instruments etc., a uniform crown of accurate dimensions on a road, highway or airport runway prior to or at the time of applying a concrete, asphalt, stone or other type of surface.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

I claim:

1. A clinometer comprising a bendable tube containing a gravity controlled element, an upper and a lower clamping member, said members having longitudinally curved faces between which the tube is gripped and curved longitudinally, the curved face of the upper of said clamping mem-

bers being transversely concaved to conform to the tube wall, said members having the walls either side of said clamping faces cut away for a substantial length between the ends thereof to reduce engagement with said tube to a narrow contact band to thereby expose a major portion of the tube surface throughout said length between the ends, and clamping means to force said clamping members into clamping engagement with said tube.

2. A clinometer comprising a bendable tube containing a gravity controlled element, a lower clamping member rockably mounted on a support structure and an upper clamping member adapted to clamp said tube to said lower clamping member, said members having longitudinally curved faces between which said tube is gripped and curved longitudinally with the curved face of the upper of said clamping members being transversely concaved to conform to the tube wall, said members having the walls at least on one side of said faces cut away for a substantial length between the ends of said members, clamping means to force said upper clamping member and tube towards said lower clamping member, and adjustable means for rocking said lower clamping member with said tube clamped thereto without upsetting curvature of said tube.

3. A clinometer comprising a bendable tube containing a gravity controlled element, a lower clamping member formed with a longitudinal precisely curved support surface for said tube pivotally mounted on a support structure, an upper clamping member adapted to clamp said tube to said precisely curved support surface, means for urging said upper clamping member to conform said tube to said longitudinal curved surface, and means to adjustably tilt said pivotally mounted lower clamping member while maintaining precise curvature of said tube against said precisely curved support surface.
